Primary Examiner — Steven J Czyz*Assistant Examiner* — Hillary Catherine Shepard(74) *Attorney, Agent, or Firm* — Fresh IP PLC; Clifford D. Hyra; Aubrey Y. Chen(57) **CLAIM**

The ornamental design for a folding table, as shown and described.

DESCRIPTION

FIG. 1 is a bottom perspective view of a folding table, FIG. 2 is an enlarged detail view of a detachable element as shown in FIG. 1;

FIG. 3 is a top perspective view thereof;

FIG. 4 is an enlarged detail view of a folding mechanism as shown in FIG. 3;

FIG. 5 is a front view thereof;

FIG. 6 is a top perspective view thereof, in an alternate condition of use; and,

FIG. 7 is an exploded top perspective view thereof.

The broken lines depict portions of the article that form no part of the claimed design.

1 Claim, 7 Drawing Sheets(56)
